CONSTANT FREQUENCY DIFFERENCE
HETERODYNEWalter van B. Roberts, Princeton, N. J., assignor
to Radio Corporation of America, a corporation
of Delaware

Application September 17, 1929, Serial No. 393,142

10 Claims. (Cl. 250—20)

My present invention relates to heterodyne circuits, and more particularly, to a superheterodyne circuit having a constant intermediate or difference frequency.

One of the most difficult problems encountered in unicontrol superheterodyne practice is that of maintaining constancy of intermediate or difference frequency. While it is true that several methods have been suggested in the past for securing a constant frequency difference in a superheterodyne circuit, yet these prior methods have not been ideal in their construction and performance.

For example, uncontrolled, straight line frequency gang condensers have been employed in the signal and local oscillator circuits of superheterodyne receivers. However, this solution necessitates the "straight line frequency" type of tuning which is not popular at present, since most of the best liked stations operate on the lower frequencies of the broadcast band, and are too much crowded into a small portion of the dial where straight line frequency tuning is employed. Also straight line frequency condensers are more bulky and difficult to manufacture than condensers such as are in common use today.

Again, attempts have been made to employ unicontrol gang condensers, the condensers all having the same shapes. Since it was extremely desirable to maintain this gang construction, electrical means of various types were employed to avoid the necessity of offsetting the oscillator condenser relative to the remaining condensers. These additional electrical means, however, were difficult to adjust, and could only result, at best, in an approximation to the desired results.

Now, I have invented a tuning arrangement for superheterodyne receivers in which all the benefits of unicontrol gang condenser construction can be retained and at the same time secure the usual and full 180° adjustment of the gang condensers, without recourse being had to any expensive or highly complicated electrical means independent of unicontrol means. That is to say, my invention provides for an adjustment to secure a constant frequency difference while adjusting the unicontrol means itself. Additionally, the nature of the means proposed hereinafter, is such that the mechanical structure of present day superheterodyne receivers employing unicontrol, gang condensers, the gang condensers being disposed in the radio frequency circuits and oscillator circuit, need not be seriously altered to embody my invention.

Accordingly, it is one of the main objects of

the present invention to provide a superheterodyne receiver embodying a unicontrol tuning means, the latter including a gang of condensers having electrodes of any desired shape, the unicontrol means, additionally, including an adjusting member operative simultaneously with the unicontrol means to maintain a constant intermediate or difference frequency.

Another important object of the invention is to provide in a superheterodyne receiver a unicontrol, gang condenser means adapted to maintain a constant difference frequency, the unicontrol means embodying an additional means, the latter being simultaneously operative with the unicontrol means and comprising a variable capacity of a predetermined magnitude and having an electrode of predetermined shape, the gang condensers including electrodes of any desired shape.

Other objects of the invention are to improve generally the simplicity and efficiency of unicontrol tuning means for superheterodyne receivers, and to provide a device of this nature which is durable and reliable in operation, economical to manufacture, and, above all, readily able to maintain an absolutely constant frequency difference.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 schematically shows a superheterodyne receiving circuit of present day construction,

Fig. 2 is a detailed view of a portion of the circuit, shown in Fig. 1, embodying one form of my invention,

Fig. 3 is a detailed view similar to Fig. 2, and shows another form of the invention,

Fig. 4 is a detailed view similar to Figs. 2 and 3 and shows the preferred form of the invention,

Fig. 5 shows one form of a specially shaped plate embodied in the invention.

Referring to the accompanying drawing in which like characters of reference indicate the same parts in the different figures, Fig. 1 schematically shows a well-known type of superheterodyne receiving circuit, in which a grounded antenna circuit A, G is connected to a tuned radio

frequency amplifier 1, the output circuit of the amplifier comprising a tunable, signal circuit S. Circuit S includes an inductance L and a variable tuning condenser C.

5 A local oscillator 2 impresses its oscillations upon the tuned input circuit S₁ of the first detector 3. The output circuit of the local oscillator 2 comprises a tunable oscillator circuit O which includes an inductance L₁ and a variable 80 capacity C₁. The input circuit S₁ of the detector 10 3 includes an inductance L₂ and a variable capacity C₂.

The output of the first detector is amplified by 15 means of an intermediate frequency amplifier 4, the output of the latter being passed through a second detector 5. The output of the latter is utilized in any well-known manner as by phonés, 100 loud-speakers, etc.

The variable capacities C, C₁, C₂ are uncontrolled in the well-known and usual manner. 20 That is to say, the rotors of these capacities are mounted in gang fashion upon a single, rotatable shaft. As explained heretofore, these three condensers should preferably be of the same shape 25 and of a shape readily produced. Furthermore, for the purposes of my invention, it is highly desirable that these three condensers be of the type universally known in the United States as the "bath-tub" gang condenser, so that no expensive 30 or extensive change must be made in present day receiver practice to embody the herein disclosed means. This type of gang condenser comprises a common metallic housing having a U-shaped cross-section, the rotor shaft being supported at 35 the opposite ends of the housing and the stators of the condenser units being secured to the sides and bottom of the housing.

In Fig. 2, I have shown a portion of the superheterodyne receiving circuit, as shown in Fig. 1. 40 That is to say I have shown the signal circuits S and S₁ and the oscillator circuit O. The signal circuit S, as shown in Fig. 1, is connected to the amplifier 1. The oscillator circuit O is connected to the oscillator tube while the circuit S₁ is connected to the detector 3.

In parallel with the variable capacity C₁ in the oscillator circuit O there is disposed a fixed capacity C₀. The three condensers C, C₁, C₂, are mounted on a single shaft, and uncontrolled, 50 as in Fig. 1. By the suitable choice of the fixed capacity C₀ in parallel with the condenser C₁ and of L₁, it is possible to obtain a fair degree of constancy of frequency difference over a portion of the broadcast range. It can be shown 55 from purely theoretical considerations that, for absolute constancy of beat frequency, the capacity in parallel with the variable condenser should be:

$$60 \quad \frac{L_1/L_2 - \left(1 + \frac{\Omega}{\omega_s}\right)^2}{L_0 \omega_s^2 \left(1 + \frac{\Omega}{\omega_s}\right)^2}$$

where, $\Omega = 2\pi \times \text{intermediate frequency} = \Omega_0 - \Omega_s$.

65 C₀ may be computed for each value of Ω_s . values of L and L₁ being assumed. For example, assume L=250; experimenting with the ratio

$$\frac{L}{L_1} = 1.62$$

70 we find C₀ runs from zero at the low frequency end, up to 23.9 and then down to 15.2 at 1500 kilocycles. If

$$\frac{L}{L_1} = 1.719$$

75 C₀ runs from 20.8 to 35 and then down to 19.

It may be pointed out here that this capacity C₀ can be obtained by having the rotor of the gang condenser pass a specially shaped plate secured to and connected to the stator. If the end rotor plate lies outside the stator, an extra plate will accomplish this purpose.

80 In Fig. 3 is shown a fixed condenser C_v in series with C₁, which also gives a certain degree of constancy of beat frequency. The constancy may be made absolute in this case, also, by adding an extra, specially shaped stator plate to C₁.

85 In Fig. 4 there is shown the preferred form of the invention. The circuits S, S₁ and O include the same tuning condensers C, C₁, C₂ and inductances L, L₁, L₂, as shown in the other figures. The oscillator circuit O has disposed therein a small, fixed capacity K in shunt with the inductance L₁, while a small variable capacity C_v is connected in parallel with the main tuning condenser C₁, the variable capacity C_v 90 being arranged for unicontrol with the main condenser. By proper choice of the fixed capacity K and the inductance L₁ the signal frequency and the superheterodyne frequency difference will be very nearly a constant amount over the 100 entire broadcasting range.

95 However, to maintain the difference frequency exactly constant, the small condenser C_v is employed, the rotor or stator plates of which condenser are specially shaped, the condenser being in parallel with the inductance L₁, and uncontrolled with the main condenser C₁. The 105 shape of the plates of the capacity C_v can readily be determined by anyone skilled in the art, one such shape being shown merely by way of illustration, in Fig. 5, it being clearly understood that the present invention is not limited to any such shape.

110 Thus, in order to adapt my invention to present superheterodyne receivers, it is merely necessary to secure a condenser embodying a 115 specially shaped plate as shown in Fig. 5 to the unicontrol tuning shaft now employed in the aforesaid receivers, the small fixed capacity K being connected in shunt with the oscillator inductance L₁, the said inductance being changed 120 slightly to conform with the value chosen for the fixed capacity K.

125 This change, as can be readily seen, involves no expensive or extensive changes in the present receivers, and does not require any change in the method of manufacture of superheterodyne receivers. It will also be understood that the elements required by my invention are inexpensive.

130 While I have indicated and described several systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

135 What I claim is:

1. A superheterodyne receiving system comprising a signal circuit and an oscillator circuit, each of said circuits being provided with a variable condenser of the same characteristics, said variable condensers having variable elements mounted upon a common varying means, a fixed capacity in parallel with the variable condenser in the oscillator circuit, and a variable condenser in parallel with said oscillator tuning condenser, 145 150

- said variable condenser being uni-controlled with said common varying means and being so designed that it maintains a constant frequency difference between the oscillator and signal circuits. 5
2. In a superheterodyne receiver, a signal circuit including a variable condenser, an oscillator circuit including a variable condenser, a common control for simultaneously and similarly varying the rotors of said condensers, a capacity connected in said oscillator circuit for maintaining the difference frequency between said signal and oscillator circuits approximately constant over the entire broadcast range, and an additional variable condenser connected in shunt to said oscillator variable condenser, and arranged for uni-control with said variable condensers, for maintaining said difference frequency exactly constant over said range. 10
3. In a superheterodyne receiver, a signal circuit including a variable condenser, an oscillator circuit including a variable condenser of the same type, a common control for simultaneously and similarly varying the rotors of said condensers, and an additional variable condenser, connected across the variable condenser in said oscillator circuit, and arranged for uni-control with said variable condensers for maintaining the difference frequency between said signal and oscillator circuits substantially constant over the entire broadcast range. 15
4. In a superheterodyne receiver, a signal circuit including a tuning device having an adjustable element, an oscillator circuit including a second tuning device of the same type having an adjustable element, a common control for simultaneously and similarly varying the adjustable elements of both tuning devices, said circuits being tunable through different frequency ranges, 20 and an additional adjustable tuning device, connected across the tuning device in said oscillator circuit, arranged for uni-control adjustment with said first two tuning devices for maintaining the difference frequency between said circuits substantially constant through said ranges. 25
5. In a superheterodyne receiver, a signal circuit including a variable condenser, an oscillator circuit including a variable condenser, a common control for simultaneously and similarly varying the rotors of said condensers, and an additional variable condenser connected in said oscillator circuit and arranged for uni-control with said variable condensers for maintaining the difference frequency between said signal and oscillator circuits substantially constant over the entire broadcast range, said additional variable condenser being connected in parallel with the oscillator circuit variable condenser. 30
6. In a superheterodyne receiver, a signal circuit including a tuning device having an adjustable element, an oscillator circuit including a second tuning device having an adjustable element, a common control for simultaneously and similarly varying the adjustable elements of both tuning devices, said circuits being tunable through different frequency ranges, and an additional adjustable tuning device, in said oscillator circuit, arranged for uni-control adjustment with said first two tuning devices for maintaining the difference frequency between said circuits substantially constant through said ranges. 35
7. In a superheterodyne receiver, a signal circuit including a variable condenser, an oscillator circuit including a variable condenser, a common control for simultaneously and similarly varying the rotors of said condensers, and an additional variable condenser connected in parallel with the variable condenser of said oscillator circuit and arranged for uni-control with said variable condensers for maintaining the difference frequency between said signal and oscillator circuits substantially constant over the entire broadcast range, said additional variable condenser including at least one electrode of a predetermined shape. 40
8. In a superheterodyne receiver, a signal circuit including a variable condenser, an oscillator circuit including a variable condenser, a common control for simultaneously and similarly varying the rotors of said condensers, and an additional variable condenser connected in shunt with the variable condenser of said oscillator circuit and arranged for uni-control with said variable condensers for maintaining the difference frequency between said signal and oscillator circuits substantially constant over the entire broadcast range, said additional variable condenser including at least one rotor element of predetermined shape. 45
9. In an electrical apparatus, the combination with a pair of tuned radio frequency circuits each comprising an inductance and a variable tuning capacity, the capacities having the same tuning characteristics and being connected for simultaneous operation through the same tuning movement range, of means for maintaining said circuits at a constant difference in frequency throughout said range, said means comprising a small fixed capacity connected in shunt with one of the tuning capacities, and an adjustable capacity, arranged for uni-control with said tuning capacities, connected in parallel with the inductance of the circuit including said one tuning capacity. 50
10. In a superheterodyne receiver, of a type comprising a signal circuit including a coil and a shunt variable tuning condenser, a local oscillation circuit including a coil and a shunt variable tuning condenser of the same type as the first, and a common adjustable control device for the rotors of both condensers, means for maintaining the intermediate frequency difference between the signal and oscillator circuits exactly constant throughout the receiver tuning range comprising a small fixed condenser in shunt with the oscillator condenser, and a small variable capacity in shunt with the oscillator coil, the rotor of the last capacity being arranged on said control device for adjustment thereby. 55
